UNITED STATES PATENT OFFICE.

LEON L. WATTERS, OF NEW YORK, N. Y., ASSIGNOR TO HOSPITAL SUPPLY COMPANY
AND WATTERS LABORATORIES CONSOLIDATED, OF NEW YORK, N. Y.

BEDPAN CLEANSER AND STERILIZER.

Application filed June 29, 1921. Serial No. 481,263.

To all whom it may concern:

Be it known that I, LEON L. WATTERS, a citizen of the United States, and a resident of the city, county, and State of New York, 5 have invented certain new and useful Improvements in Bedpan Cleansers and Sterilizers, of which the following is a specification.

One of the purposes of this invention is 10 to produce an apparatus for thoroughly cleansing and sterilizing articles used in hospitals, particularly with reference to bedpans, in which it is desirable to dispose of the contents quickly and in a sanitary manner.

Another object is to provide an apparatus 15 with means for the inlet of water sprays under an adequate pressure, rotate the article to be cleansed so that all parts are subjected to the spray and finally to introduce steam for sterilization purposes to such extent as is necessary.

A further aim is in the provision of means for hermetically sealing the apparatus 20 during the processes of cleansing and sterilizing so that no odor or emanations may issue and to so mount the apparatus that all débris and liquids used in cleansing are conducted directly to the drain which 25 forms a support or pedestal of unique character.

These and other analogous objects, which 30 will become apparent as the description progresses, are attained by the novel construction, combination and arrangement of parts, 35 hereinafter described and shown in the accompanying drawings, forming a material part of this disclosure, and in which:—

Figure 1 is a front elevational view of an 40 apparatus embodying the invention, parts being broken away to disclose the construction.

Figure 2 is a side elevational view thereof, the cover being shown in raised position.

Figure 3 is a transverse sectional view 45 taken on line 3—3 of Figure 1.

Figure 4 is a side view of the bed-pan, showing in detail the clamp and its revolving means.

Figure 5 is a plan view thereof.

Figure 6 is a side view of the same, the parts being shown reversed from that shown in Figure 4.

Figure 7 is a fragmentary side elevational view of a modification of construction. 55

Figure 8 is an enlarged fragmentary sectional view of the lower steam inlet.

Stated briefly in general terms, the apparatus comprises a cylindrical tank having a concave bottom, the top being open and 60 provided with a band to which is hingedly engaged a cover and means for clamping the same thereover when in operation.

In place of legs or supports, as commonly used, the tank is permanently engaged upon 65 a special type of drain trap fitting which communicates directly with sewer connections so that no effluvia may escape during operation, and because of the peculiar mounting employed, the floor is easily kept 70 clean.

Intermediate the trap fitting and tank is a valve independently operated in flushing the tank, which is provided with means for the separate inlet of water and steam under 75 complete control of the operator.

The tank band is furnished with a gasket making air tight connection with the cover and is provided with pedally operated means for opening and closing, thus leaving the hands free for other purposes. 80

Mounted to rotate on a horizontal axis in the tank is a cradle to which the bed-pan may be securely clamped and a crank extends into position to be conveniently manipulated for this purpose. 85

Referring now more specifically to the drawings, the numeral 15 designates the flanged base of a water sealed trap body 16, provided with a removable plug 17 at 90 the front and an outlet branch 18 at the rear in which is engaged a sewer pipe connection 19.

The vertical branch 20 of the trap engages the lower end of a valve body 21, its 95 rotatable plug 22 being provided with a stem 23 having an operating hand lever 24 and the upper end of the valve body engages the base flange of the tank 25.

The pedestal thus provided is preferably 100

finished in smooth white enamel while the tank body is of copper, plated if preferred and formed without seams, the concave lower portion having united to it a base flange 5 26.

At the upper edge of the tank is secured a circumjacent band or ring 27 containing an annular recess in which is disposed a gasket or pliable packing 28, against which 10 the edge of the ring portion 29 of the cover or lid 30 makes contact.

This cover is formed concavo-convexly from sheet metal, like that of the tank, and is provided with a rigid loop 31 at the center, in which is engaged a lever 32, curved in conformity with the cover and held in the loop by a transverse pivot pin 33.

The rear extending end 34 is pivoted by a pin 35 passing through a fork 36, formed 20 with the band 27, and its front end 37 is adapted to be engaged by a loop or catch 38 pivoted to lugs 39 extending from the band diametrically opposite the fork 36, the clamp loop 38 having an operating 25 handle 40.

A rearward extension 41 of the lever 32 is pivoted to one end of a link 42 and the opposite end of the link is pivotally engaged with a yoke 43 in turn pivoted at its ends 30 to brackets 44 fixed on the wall of the tank.

A spindle 45, connecting the link 42 to the yoke, has attached to its ends, a pair of rods 46 which extend downwardly and to the front, on opposite sides, of the 35 pedestal and pivotally engage levers 47, in turn pivoted on a rod 48 fixed in the rear portion of the trap 16, the front ends of the levers being fixed to a pedal 49.

Due to the pivotal connection of the cover 40 to the lever 32, the cover is self-adjustable and may be clamped to form an impervious joint on the edge of the tank. When the clamp 38 is released and the pedal 49 depressed it is evident that the cover will be 45 raised, affording a clear opening to the tank.

A stud 50 is fixed in the tank at the rear, midway its length, the stud acting as a pivot for a bar 51, having its ends 52 and 53 bent at right angles, the front end 53 having 50 fixed in it a spindle 54 extending through the wall of the tank and engaged with a manually operable crank handle 55.

Cross arms 56 are secured at the center of the bar 51, the bar and arms having near 55 their ends lugs 57 in which are secured a seat or guide ring 58 formed of a wire bent to engage the article to be cleansed, and which is thus suspended so that its weight is below the axis of the supporting pivots and 60 hangs pendent thereby facilitating the entrance or removal of the article to be cleansed.

A post 59 is raised from the bar 51, near the angle end 52 and pivoted in the post

is a trap 60 forked at its front end to engage a projection 61 raised from the bar 51 near its front end and having a snap catch 62 engageable with the strap at the bottom of the prongs 63 forming the hook. 65

Fixed to the strap, near the fork, is a 70 forked lug 64 in which is pivotally mounted a hand lever 65, its curved point 66 being positioned to engage and release the catch 62 when the lever is depressed and thereby free the strap permitting the article clamped 75 by it to be removed.

Engaged centrally of the strap 60 is a fixed stud 81 to which is attached upper and lower leaf springs, respectively 82 and 83, adapted to make resilient contact with the 80 upper surface of the pan, holding it firmly in engagement with the seat ring 58, when the strap is clamped thereover.

At a point opposite one side of the work holder or cradle just described, a plate 67 is secured by its flanged edge interiorly 85 the tank, the spaced portion of the plate containing a plurality of perforations 68.

This plate covers the opening of a flange 69 fixed on the outside of the tank and engaging a pipe 70 controlled by an angle valve 71, the outer inlet of which is connected with a water supply pipe 72. 90

Below the water inlet is a steam inlet pipe 73 entering the tank 25 at a point above 95 its curved lower portion, this pipe being a branch of another steam pipe 74 entering the lower portion of the tank 25, the inlet of steam being controlled by a valve 75, the pipe 76 beyond the valve leading to a boiler 100 from where a supply of steam can be obtained.

The purpose of the double steam inlets is to prevent noise caused by a single inlet, particularly if water be present in the tank, 105 the water passing down in the pipe to the T 97 where steam enters through the passage in the valve 75 and is directed centrally of the pipe 74 by the conical element 98, acting as a type of injector, preheating the water which is mingled with the steam, and entering the tank without noise, thus affording means for thoroughly sterilizing the pan and contents of the tank as will be understood. 110

A combined over-flow and vent pipe 77 communicates with the tank at its rear, directly behind the looped bracket 96 which carries the pivot pin 50, the pipe leading to a T fitting 78 having a removable plug 120 79 in its upper through end and another pipe 80 in its lower end, entering the drain connection 16, thereby limiting the accumulation of water in the tank and also acting as a vent to the same. 115

In the modification, shown in Figure 7, the tank and its interior parts remain the same as previously described, as is also the

pedestal and interposed valve 21 and is provided with a steam jacket for heating the same.

The valve is formed with a hollow projection 85 terminating in the bottom of the tank and passing through a chamber 86, formed by a plate 87, riveted as at 88 to the curved bottom of the tank, the plate being spaced as shown.

10. In this case the steam pipe 73 is provided with an independent control valve 89 and the lower steam inlet pipe 90, also has a valve 91, the lower inlet communicating direct with the chamber 86, which is provided with an outlet 92 returning to the source of steam supply.

This arrangement provides means for merely heating the tank, by opening the valve 91, or for entering steam by the valve 20 89 as may be desired.

As changes of construction could be made within the scope of the invention, it is intended that all matters contained in the foregoing description or shown in the accompanying drawings shall be interpreted as illustrative and not in a limiting sense, it being obvious that changes, not involving the exercise of invention, may be made without conflicting with the scope of the appended claims.

Having thus described my invention, what I claim as new and desire to secure by Letters Patent, is:—

1. An apparatus comprising a tank having a hinged cover, a gasket carried by the rim of said tank, means for clamping the cover to form an impervious joint with said tank, a work holder revolvably mounted in the tank, means for manually actuating said holder, means for spraying the work carried in the holder, a hollow pedestal on which said tank is mounted, a drainage means connected with said pedestal, and pedally operated means for raising said cover.

2. An apparatus comprising a vertical cylindrical tank having a cover adapted to form an impervious joint thereover, a foot lever for raising said cover, a hollow pedestal on which said tank is mounted, said pedestal having an expanded base above the floor and containing a passage leading from the tank to a drain, means for positively controlling the mentioned passage, a work holder mounted on a transverse axis in said tank, means for completely rotating said holder, controlled means for the admission of water directed against work in said holder, other controlled means for the admission of steam to said tank at a point below the water inlet, and a combined vent and overflow for said tank, entering said hollow pedestal.

3. An apparatus comprising a vertical

cylindrical tank having an impervious cover 65 removably engaged, separate means independently controllable for the admission of water and of steam to said tank, a work holder disposed transversely in the tank, a pivoted spring clamp bar on said holder for positively clamping work therein, a crank by which said holder may be completely and continuously rotated in either direction on a transverse axis, means for draining said tank into a sewer, a rotary valve controlling 70 said draining means, and a combined vent and overflow from said tank entering said draining means.

4. An apparatus composed of a vertical cylindrical tank, a domed cover therefor, a curved bar hinged near one end to said tank, a clevis fixed axially on said cover engaging said bar by a transverse pivot, brackets on said tank, a yoke pivoted in the brackets, a spindle fixed in the end of said yoke, a link 80 connecting said spindle with the extending end of said bar, rods at the ends of said spindle, a trap in communication with said tank, levers pivoted to said trap, said levers being pivotally engaged by said rods, a 85 pedal connecting said levers, and a loop pivoted to said tank engageable with the free end of said bar whereby said cover may be held in firm engagement with the edge of 90 said tank.

5. An apparatus comprising a stationary tank connected with an axial drain, an intercepting valve in the passage therebetween, means for the inlet of water to the tank, a heating chamber below said tank, 100 means for the inlet of steam to the tank, and to said chamber, a combined overflow and vent pipe communicating between the upper portion of said tank and the drain, and a drain for said chamber.

6. In an apparatus of the class described, the combination with a stationary tank, a work holder pivoted to rotate on a horizontal axis therein, said support comprising a plurality of arms disposed in a plane below its pivotal supports, a ring carried by said arms adapted to receive a bed pan, a strap hinged over said arms, means for detachably engaging said strap when in operative position, and one or more leaf springs carried by said strap adapted to retain a bed pan in said ring.

7. A bed pan support comprising a frame having four equally divergent arms, two of said arms being opposite and having raised end lugs, pivots engaging said lugs above the plane of said arms, a ring carried by said arms adapted to engage a pan, a resilient strap for clamping a pan on said ring, a spring hook engaging said strap, a lever releasing means for said hook, and means for rotating said frame on its pivots.

8. A bed pan support comprising a plural-

ity of radial arms, pivots in the ends of one pair of diametrically opposite arms, said pivots being mounted above the plane of the arms, a seat ring carried by the arms, a post
5 on one of said arms, a strap hinged to said post, a resilient catch opposite said post adapted to engage the free end of said strap,

means on said strap for disengaging said catch, and means for rotating said support upon its pivots.

In testimony whereof, I have signed my name to this specification.

LEON L. WATTERS.
